US0D1097729S

(12) **United States Design Patent** (10) Patent No.: **US D1,097,729 S**
(45) Date of Patent: ** Oct. 14, 2025

(54) **MULTIPLE-USE MOLD**

(71) Applicant: **Lihua Ye**, Foshan (CN)

(72) Inventor: **Lihua Ye**, Foshan (CN)

(**) Term: **15 Years**

(21) Appl. No.: **29/983,749**

(22) Filed: **Jan. 12, 2025**

(30) **Foreign Application Priority Data**

Nov. 6, 2024 (CN) 202430702582.2

(51) **LOC (15) Cl.** **07-02**

(52) **U.S. Cl.**

USPC **D7/675**

(58) **Field of Classification Search**

USPC D7/357, 503, 505, 506, 555, 556, 672,
